UNITED STATES PATENT OFFICE.

JOSIAH LUCUS JONES, OF NEW CASTLE, NEW HAMPSHIRE.

STUMP-PULLER.

No. 851,521.

Specification of Letters Patent.

Patented April 23, 1907.

Application filed November 9, 1906. Serial No. 342,640.

To all whom it may concern:

Be it known that I, JOSIAH LUCUS JONES, a citizen of the United States, and a resident of New Castle, in the county of Rockingham and State of New Hampshire, have invented a new and Improved Stump-Puller, of which the following is a full, clear, and exact description.

This invention relates to improvements in machines for pulling tree stumps, the object being to provide a stump puller on which a motor is mounted and adapted for use in moving the machine from place to place, and also to furnish power for pulling stumps.

I will describe a stump puller embodying my invention, and then point out the novel features in the appended claims.

Reference is to be had to the accompanying drawings forming a part of this specification, in which similar characters of reference indicate corresponding parts in all the figures.

Figure 1 shows in plan a stump puller embodying my invention; Fig. 2 is a side elevation thereof partly in section; Fig. 3 is a plan of a fifth wheel and steering mechanism employed; Fig. 4 is a section on the line 4—4 of Fig. 3; Fig. 5 shows a fastening block that may be employed for attaching a cable to stumps; and Figs. 6 and 7 are detail views showing different ways of attaching the cable.

Referring to the drawings, 5 designates the frame of the machine which may consist of any suitable material. In case the frame is made of wood it may be strengthened by a band or rod 6 of metal which engages around the outer side of the frame or is seated in a channel therein, and the rear end of the rod receives the shaft of the winding drum to be hereinafter described, so that the strain on the winding drum will not bear wholly on the wooden frame. The rear portion of the frame is supported by wheels 7 which are rigidly connected to the axle 8, and at the forward end the frame is supported by a steering wheel 9 having its axle bearings in hangers 10 depending from a fifth wheel 11 arranged for rotary motion on the under side of the frame, the said rotary motion being around a king bolt 12. As a means for turning the fifth wheel and consequently shifting the steering wheel, the said fifth wheel is provided with a segment rack 13 engaged by a pinion 14 on the lower end of a shaft 15 which extends upward and is provided with a hand wheel 16 within easy reach of an operator on a seat 17 mounted on the machine.

Having bearings in the forward portion of the machine frame is a driving shaft 18 that may be operated by any suitable means. I have here indicated a motor 19 mounted on the machine, the said motor being operated as a gas engine or otherwise, and on this shaft 18 is a fly-wheel 20. The operation of the motor may be somewhat regulated by means of a friction lever 21 attached to the machine and adapted to be pressed downward by foot power upon a collar 22 above said shaft; also on the shaft 18 is a pinion 23 meshing with a gear wheel 24 on a counter shaft 25 and on this counter shaft 25 is a pinion 26 meshing with a gear wheel 27 loosely mounted on the axle 8. Rigidly connected to the gear wheel 27 is a pinion 28 meshing with a gear wheel 29 on a shaft 30 extended transversely of the machine frame and movable lengthwise on the shaft 30, but adapted to rotate therewith is a pinion 31. As here shown, the pinion 31 engages with an annular portion 32 on said shaft and it may be moved lengthwise of the shaft to engage it with or disengage it from the drum gear wheel by means of a lever 33 mounted to swing on the frame and having a forked end engaging in the channel formed in the hub portion 34 of said pinion 31. When the machine is in operation for pulling the stump, the pinion 31 is to be moved into mesh with the gear wheel 35 on the shaft 36 of the winding drum 37. It will be noted in Fig. 1 that the drum 37 has a spirally disposed channel 38 in which the pulling cable 39 is guided and by this arrangement the strain upon the cable is divided equally on its several strands.

When it is desired to move the machine from one place to another, the gear wheel 27 is to be placed in locked connection with one of the wheels 7. This locking device consists of a latch rod 40 movable in guides carried by a spoke of the gear wheel 27 and having its end turned outward to be engaged with a pin 41, also on said spoke to hold the locking latch out of engagement with the hub and against the resistance of a spring 42 which tends to force the latch toward the hub to hold the same in engagement with any one of a series of notches 43 formed in the wheel hub.

In the operation the machine is to be anchored in any suitable manner. I have here shown a rope or cable 44 extended from the front of the frame and adapted to engage around a stump 45. The pulling cable 39 is

then engaged with the stump to be pulled. Of course, at this time the latch connection between the gear wheel 27 and the main wheel 7 will be out of its locking position and 5 the pinion 31 in mesh with the gear wheel 35, so that upon starting the motor the drum will be rotated. When the machine is to be taken from one place to another the pinion 31 is to be shifted out of engagement with 10 the gear wheel 35 and the gear wheel 27 locked to the supporting wheel 7. Then, of course, the motor will cause a forward movement of the machine. The pulling or drawing cable may be attached to a stump by any 15 suitable means. Preferably, however, to prevent possible breaking thereof, I employ a segmental block 46 around which one end of the cable may be secured and on this block is a hook 47 for engaging with the cable 20 passed around the stump, as indicated in Fig. 6. In some instances it may be necessary to pass the cable around the sheave 48 attached to a short rope or cable 49 which is 25 passed around the anchoring stump, as indicated in Fig. 7.

It will be noted in Fig. 3 that one side of the fifth wheel 11 is cut away to permit the passing therethrough of the gear wheel 24.

Having thus described my invention, I 30 claim as new and desire to secure by Letters Patent:

1. A stump pulling machine comprising a frame, supporting wheels therefor, a driving shaft on the frame, a countershaft on the 35 frame, a connection between the driving shaft and the countershaft, a gear wheel

loosely mounted on the axle of the rear wheels, means for locking said gear wheel to one of said wheels, a connection between the countershaft and the gear wheel, a transverse shaft on the frame, means for connecting the gear wheel with the transverse shaft, a winding drum carried by the frame, and a releasable connection between the winding drum and the transverse shaft. 40

2. A stump pulling machine, comprising a frame, rear supporting wheels therefor, a front supporting and steering wheel, a driving shaft on the frame, a pinion on said driving shaft, a counter shaft, a gear wheel on the 50 counter shaft meshing with said pinion, a pinion on the counter shaft, a gear wheel loosely mounted on the axle of the rear wheels, means for locking said last-named gear wheel in connection with one of the said 55 wheels, a pinion carried by said gear wheel, a transverse shaft on the frame, a gear wheel on said transverse shaft meshing with said pinion, a pinion movable lengthwise on the transverse shaft but adapted to rotate therewith, a winding drum carried by the frame, and a gear-wheel on the shaft of the driving drum adapted to be engaged by said last-named pinion. 60

In testimony whereof I have signed my 65 name to this specification in the presence of two subscribing witnesses.

JOSIAH LUCUS JONES.
